UNITED STATES PATENT OFFICE

OTTO F. FOGELSTRAND, OF KENSINGTON, CONNECTICUT, ASSIGNOR TO
HART MANUFACTURING COMPANY, OF SAME PLACE.

DESIGN FOR BLOWER-STAND.

Specification forming part of Design No. 6,194, dated October 8, 1872.

To all whom it may concern:

Be it known that I, OTTO F. FOGELSTRAND, of Kensington, in the county of Hartford and State of Connecticut, have invented a Design for a Blower-Stand, of which the following is a specification:

The nature of my design is fully represented in the accompanying engraving, to which reference is made.

A A represents the end pieces, and B their connecting bar. The edges of the bar B are ornamented by alternate carved depressions and planes, as fully shown in the drawing. The sides of the bar B are bordered by a plain ledge, inside of which border and opposite the planes, upon the edge, are straight ledges, crossing each other in the form of an X. The groundwork of all the parts which are ornamented in relief consists of fine raised check-work, having a raised point in the center of each square.

The contour of the end pieces A A is as follows: Commencing at the center of the deep vertical slot, it runs to one side in a horizontal plane; then upward, in a vertical line over the top, in a waved and curved line; then following down upon the outside in a vertical plane; then follows an ovolو; then a horizontal plane; then a cove; then a vertical plane; then a cove; then a horizontal

plane; then an ogee; then a short vertical plane; then an ogee; then a horizontal plane across the base of the foot; then upward is an ogee; then a short vertical plane; then an ogee; then a short vertical plane; then an ovolو; then a horizontal plane; and then in a curved line to a point in the center between the feet of the end piece, which is the contour of one-half the end piece A, and the other half is a counterpart of the same. These end pieces are bordered by a plane ledge, inside of which border, at the feet and near the top, are straight ledges, which cross each other in the form of diamonds and half diamonds, from which extends raised scroll-work. Extending from the corner of the upper ovolو and horizontal plane is scroll-work in relief, and at the central portion of the end pieces is a figure of scroll and leaf work in relief, which meets at a point projecting upward at the upper side of said figure. The whole are combined and arranged, as clearly shown in the drawing, to form a new design for a blower-stand.

I claim as my invention—

The design for a blower-stand as herein described, and shown in the drawing.

OTTO F. FOGELSTRAND.
